β,β -DICYANO- α -HYDROXYVINYL ORGANIC ACIDS

**William Joseph Middleton, Wilmington, Del., assignor to
E. I. du Pont de Nemours and Company, Wilmington,
Del., a corporation of Delaware**

**No Drawing. Application March 16, 1954,
Serial No. 416,718**

6 Claims. (Cl. 260—326.5)

This invention relates to organic acids and their preparation and, also, to salts of organic acids.

It is known that many organic carboxylic acids are strong acids in a water system. This is particularly true of those carboxylic acids which are in some way activated by the presence of a functional group other than carboxyl in the molecule. A well-known example is trichloroacetic acid which is among the strongest of the carboxylic acids ($pK_a=1.1$, Branch, G. E. K., and Calvin, M., "The Theory of Organic Chemistry," Prentice-Hall, Inc., New York, 1946, page 224). It is further known that there are some carboxyl-free organic compounds which are capable of dissociating as acids in a water system because they possess a hydrogen atom sufficiently activated by other structures in the molecule. Numerically, this is a relatively minor group of organic acids and one which has received little commercial attention to date.

An object of the present invention is to provide a new class of organic acids and their salts. A further object is to provide a process of preparing such acids. A still further object is to provide a new class of carboxyl-free organic acids. Other objects will be apparent from the description of the invention given hereinafter.

The above objects are accomplished according to the present invention by hydrolyzing in alkaline medium C-tricyanovinyl compounds in which the C-tricyanovinyl group is attached to a carbon of either a 5-membered N-heterocyclic or 6-membered carbocyclic organic ring, to yield the alkaline salts of the corresponding beta,beta-dicyano-alpha-hydroxyvinyl compounds and then acidifying the alkaline medium to precipitate the corresponding beta,beta-dicyano-alpha-hydroxyvinyl organic acids.

Due to the strong acidity of the $-\text{OH}$ group attached to the carbon doubly bonded to the dicyano carbon, these compounds are all acids. They may or may not contain a carboxyl ($-\text{COOH}$) group in addition. A preferred group of these acids are those in which the beta,beta-dicyano-alpha-hydroxvvinyl radical

is attached to a carbon of a 6-membered carbocyclic or a 5-membered N-heterocyclic organic ring which is aromatic.

While it is desired to place no limitation on the present invention by theoretical speculations, it is postulated that the acid character of the beta,beta-dicyano-alpha-hydroxyvinyl compounds of this invention involves dissociation of the hydrogen of the hydroxyl group. It is possible that these beta,beta-dicyano-alpha-hydroxyvinyl compounds may represent a tautomeric mixture as indicated by the following equilibrium:

However, infrared spectral examination of the particular compounds of the present invention gives strong evidence for a structure of form I and no detectable evidence for a structure of form II. The strong acidity of the compounds of the present invention is especially surprising since the known 1,1-dicyanoacetone (where R=methyl) is a weak acid which has been shown to exist only up to 3.3% in the enolic form I.

The invention can be carried out by digesting the C-10 tricyanovinyl compound with aqueous alkali until it is converted to the alkali salt of the corresponding beta, beta-dicyano-alpha-hydroxyvinyl compound as evidenced by obtaining a clear aqueous solution. The free beta, beta-dicyano-alpha-hydroxyvinyl compound is obtained 15 as a precipitate when the solution is acidified. This process may be illustrated by the following equation:

The C-tricyanovinyl compounds used as starting materials in the present invention are characterized by having the grouping $(CN)_2C=C(CN)C$ as distinguished from the N-tricyanovinyl compounds characterized by having a grouping $(CN)_2C=C(CN)N$. These C-tricyanovinyl compounds are prepared according to the disclosures in U. S. applications Serial Nos. 382,857, now abandoned; 382,858; and 382,860, all filed September 28, 1953 in the name of R. E. Heckert.

30 The following examples in which all proportions are by weight unless otherwise stated, illustrate the preparation of organic acids according to the present invention.

Example 1

2-tricyanovinyl-1-methylpyrrole, 25 parts, is added to 277 parts of 10% aqueous sodium hydroxide, and the mixture is warmed gently for 2 or 3 minutes until solution is complete. The light yellow solution of the sodium salt of 2-(beta,beta-dicyano-alpha-hydroxyvinyl)-1-methylpyrrole is cooled and then acidified with hydrochloric acid. The white precipitate which forms is collected on a filter, washed with water, and recrystallized two times from water to give 10 parts of 2-(beta,beta-dicyano-alpha-hydroxyvinyl)-1-methylpyrrole in the form of matted white needles. M. P. 158° C.-159° C.

Anal.—Calc'd. for $C_9H_7N_3O$: C, 62.42; H, 4.07; N, 24.22; Neut. Equiv., 173.17. Found: C, 62.19, 62.09; H, 4.34, 4.38; N, 24.23, 24.08; Neut. Equiv., 170.2, 171.5.

50 The infrared absorption spectrum indicates an —OH at 2.9 microns but shows no absorption due to a carbonyl. The molecular extinction coefficient at 315 millimicrons is 15,540. The ultraviolet absorption measurements on which the molecular extinction coefficient is based, were made on a Cary recording spectrophotometer built by the Applied Physics Corporation of Pasadena, California. The terms used are explained on page 4, "Chemical Spectroscopy" by W. R. Brode, John Wiley & Sons, New York 1939.

60 As further confirmation of the identification of this product, 20 parts of the above 2-(beta,beta-dicyano-alpha-hydroxyvinyl)-1-methylpyrrole is dissolved in 555 parts of 10% aqueous sodium hydroxide, and the solution is heated under reflux for 18 hours. The solution is cooled
 65 and acidified with hydrochloric acid. A white precipitate forms which is recrystallized from water. There is obtained 5 parts of 2-(beta-carbamyl-beta-cyano-alpha-hydroxyvinyl)-1-methylpyrrole in the form of white needles, M. P. 158°C.-160°C.

Anal.—Calc'd. for $C_9H_9N_3O_2$: C, 56.54; H, 4.75; N, 21.98; Neut. equiv., 191.18. Found: C, 56.29, 56.45; H, 4.71, 4.60; N, 22.05, 22.25; Neut. equiv., 195.2, 194.8.

Example II

A solution of 40 parts of 4-tricyanovinyl-2,6-dimethylphenol in 1109 parts of 10% sodium hydroxide is warmed momentarily to 90° C. and then quickly cooled and acidified with hydrochloric acid. The precipitate which forms is collected on a filter, washed with water, and recrystallized from alcohol-water. There is obtained 20 parts of 4-(beta,beta-dicyano-alpha-hydroxyvinyl)-2,6-dimethylphenol in the form of light pink matted needles, M. P. 236° C.-238° C.

Anal.—Calc'd. for $C_{12}H_{10}N_2O_2$: C, 67.28; H, 4.71; N, 13.08; Neut. equiv., 214.22. Found: C, 66.93, 66.84; H, 4.74, 4.71; N, 13.10, 12.95; Neut. equiv., 216.4.

$pK_a=2.55$.

Example III

A solution of 58 parts of 4-(tricyanovinyl)-N,N-dimethylaniline in 277 parts of 10% aqueous sodium hydroxide and 79 parts of ethanol is heated to reflux temperature and then cooled immediately in ice. The orange-brown precipitate of the sodium salt of 4-(beta,beta-dicyano-alpha-hydroxyvinyl)-N,N-dimethylaniline which separates, is recrystallized several times from dilute sodium hydroxide, using charcoal for decoloration until the product is pale yellow (27 parts, 44%). Acidification of an aqueous solution of this material gives 4-(beta,beta-dicyano-alpha-hydroxyvinyl)-N,N-dimethylaniline in the form of pale yellow needles, M. P. 210° C.-211° C.

Anal.—Calc'd. for $C_{12}H_{11}N_3O$: C, 67.59; H, 5.70; N, 19.71. Found: C, 67.68, 67.57; H, 5.63, 5.33; N, 20.21, 20.16.

$pK_a=2.26$.

A solution of 20 parts of this 4-(beta,beta-dicyano-alpha-hydroxyvinyl)-N,N-dimethylaniline in 590 parts of ethanol saturated with hydrogen chloride is refluxed for 5 hours. The ammonium chloride which forms is removed by filtration, and the filtrate is evaporated on a steam cone to about $\frac{1}{4}$ its original volume and then poured into cold 10% sodium hydroxide solution. The pale yellow precipitate which forms is collected on a filter and recrystallized from ethyl alcohol. There is obtained 18 parts of ethyl p-(dimethylamino)benzoate, M. P. 64° C.-64.5° C. The infrared spectrum of this compound is

$pK_a=2.26$.

identical with that of an authentic sample of ethyl p-(dimethylamino)benzoate.

Example IV

A solution of 50 parts of 4-(tricyanovinyl)-N-methylaniline in 330 parts of 10% aqueous sodium hydroxide and 79 parts of ethanol is heated to boiling and then cooled immediately in ice. The orange precipitate of the sodium salt of 4-(beta,beta-dicyano-alpha-hydroxyvinyl)-N-methylaniline which forms is recrystallized several times from dilute sodium hydroxide. An aqueous solution of this sodium salt is acidified with hydrochloric acid. The white precipitate which forms, is collected on a filter, washed with water, and recrystallized from ethanol to give 4-(beta,beta-dicyano-alpha-hydroxyvinyl)-N-methylaniline in the form of pale yellow crystals, M. P. 228° C.-230° C.

Anal.—Calc'd. for $C_{11}H_9N_3O$: C, 66.32; H, 4.55; N, 21.03. Found: C, 66.36, 66.36; H, 4.59, 4.69; N, 21.00, 20.94.

$pK_a=3.35$.

Example V

A solution of 14 parts of 4-(tricyanovinyl)-2,6-dimethylaniline in 110 parts of 10% sodium hydroxide and 24 parts of ethanol is heated momentarily to boiling and then quickly cooled in ice. An orange-yellow precipitate of the sodium salt of 4-(beta,beta-dicyano-alpha-hydroxyvinyl)-2,6-dimethylaniline forms. An aqueous solution of this sodium salt is acidified, and the resultant white precipitate is collected on a filter, washed with water, and recrystallized from ethanol. There is obtained 9.5 parts of 4-(beta,beta-dicyano-alpha-hydroxyvinyl)-2,6-dimethylaniline in the form of colorless crystals, M. P. 300° C.

Anal.—Calc'd. for $C_{12}H_{11}N_3O$: C, 67.59; H, 5.20; N, 19.71. Found: C, 67.50, 67.61; H, 5.36, 5.42; N, 19.50, 19.57.

$pK_a=3.05$.

Examples of other C-tricyanovinyl starting materials and the beta,beta-dicyano-alpha-hydroxyvinyl compounds obtained from them according to the present invention, are shown in the following table.

Table I

Starting Compound	Product
2-Tricyanovinylpyrrole.....	 2-(β,β -dicyano- α -hydroxy-vinyl)pyrrole
3-Tricyanovinyl-2,5-dimethylpyrrole.....	 3-(β,β -dicyano- α -hydroxyvinyl)-2,5-dimethylpyrrole
N-(β -cyanoethyl)-N-methyl-p-tricyanovinylaniline.	 N-(β -cyanoethyl)-N-methyl-p-(β,β -dicyano- α -hydroxyvinyl)aniline
N-butyl-N-(β -cyanoethyl)-p-tricyanovinylaniline..	 N-butyl-N-(β -cyanoethyl)-p-(β,β -dicyano- α -hydroxyvinyl)aniline
N-(β -cyanoethyl)-o-methyl-p-tricyanovinylaniline.	 N-(β -cyanoethyl)-o-methyl-p-(β,β -dicyano- α -hydroxyvinyl)aniline

Starting Compound	Product
N-phenyl-p-tricyano-vinylaniline.....	
N-phenyl-m-hydroxy-p-tricyanovinyylaniline.....	
N-(p-tricyanovinyl-phenyl)ethanolamine.....	
6-Trieyanovinyl-1,2,3,4-tetrahydro-quinoline.....	
2-Tricyanovinyl-4-methylphenol.....	
2-Tricyanovinyl-4,6-dimethylphenol.....	

It will be understood that the above examples are merely illustrative and that the present invention broadly comprises hydrolyzing in alkaline medium a C-tricyanovinyl compound in which the C-tricyanovinyl group is attached to a carbon of either a 6-membered carbocyclic or 5-membered N-heterocyclic organic ring, to yield the salt of the corresponding beta,beta-dicyano-alpha-hydroxyvinyl compound and then acidifying the alkaline medium to precipitate the corresponding free beta,beta-dicyano-alpha-hydroxyvinyl acid, and in these new acids and the salts thereof.

The reaction of this invention is broadly applicable to any C-tricyanovinyl compound providing the C-tricyanovinyl group is attached to a carbon of either a 6-membered carbocyclic or 5-membered N-heterocyclic organic ring and, consequently, there can be obtained the corresponding free acid or salt thereof. The examples disclose numerous C-tricyanovinyl compounds of the type adapted for use in the present invention, and the corresponding acids formed.

The alkaline digestion step of the process of the present invention is readily carried out at ordinary temperatures. For more rapid completion of this step, the reaction may be carried out at a temperature within the range of 50° C. to 100° C. Temperatures in excess of 100° C. may also be employed, provided a closed vessel is used which is capable of withstanding the autog-

50 enous pressures developed. There is ordinarily no advantage obtained by operating at temperatures in excess of 100° C., and at any temperature above room temperature care must be taken to stop heating the reactants as soon as the beta,beta-dicyano-alpha-hydroxyvinyl compound is obtained since prolonged heating with strong 55 alkali may destroy it. Pressure is not critical.

A wide variety of alkaline materials can be used in the process of the present invention. For example, the hydroxides or the carbonates of the alkali and alkaline earth metals may be used. Other alkaline materials can be used, such as ammonia and amines, particularly the quaternary ammonium hydroxides. In general, any agent which is a good source of hydroxyl ions can be employed.

It is convenient to employ water as a liquid medium for carrying out the process of the present invention, 60 but other liquid media can also be employed, such as aqueous solutions of water-miscible organic compounds, such as alcohols and phenols. Alternatively, the alkaline hydrolysis reaction can be carried out in the absence of water if desired. For example, the C-tricyanovinyl 65 compound can be digested with a solution of potassium hydroxide in ethyl alcohol and the resulting potassium salt of the beta,beta-dicyano-alpha-hydroxyvinyl compound can be converted to the free hydroxy compound by passing in anhydrous hydrogen chloride until the mixture has been acidified.

The compounds of the present invention possess unique utility as self-indicating acids for conducting acid-base titrations. In the titration of aqueous systems containing the products of the present invention, there is a point of inflection of pH, characteristic of each of these products, at which there is a sharp shift from colorless to colored forms or vice versa. These shifts are visible by ordinary light when using the phenolic types, such as the color change which takes place at a pH of 5.75 in dilute aqueous solutions of 4-(beta,beta-dicyano-alpha-hydroxyvinyl) - 2,6 - dimethylphenol, the product from Example II. With the others, this color shift is readily observed by optical examination of the system under ultraviolet light. In this way the quantitative determination of an alkaline material can be readily made by titrating with one of the acids of the present invention. Such a titration permits improved accuracy by eliminating the side reaction necessary to produce the color change in an extraneous indicator.

As many apparently widely different embodiments of this invention may be made without departing from the spirit and scope thereof, it is to be understood that the invention is not limited to the specific embodiments thereof except as defined in the appended claims.

The invention claimed is:

1. A compound selected from the class consisting of beta,beta-dicyano-alpha-hydroxyvinyl organic acids and their salts, in which the alpha-carbon of the vinyl group is attached to a carbon of a ring selected from the group consisting of 5-membered N-heterocyclic and 6-membered carbocyclic rings.

2. A compound selected from the class consisting of beta,beta-dicyano-alpha-hydroxyvinyl organic acids and their salts, in which the alpha-carbon of the vinyl group is attached to a carbon of a pyrrole ring.

20

25

30

35

3. A compound selected from the class consisting of beta,beta-dicyano-alpha-hydroxyvinyl organic acids and their salts, in which the alpha-carbon of the vinyl group is attached to a carbon of a benzene ring.

4. Process of preparing a beta,beta-dicyano-alpha-hydroxyvinyl organic acid, which comprises hydrolyzing in alkaline medium a C-tricyanovinyl compound in which the C-tricyanovinyl group is attached to a carbon of a ring selected from the group consisting of 5-membered N-heterocyclic and 6-membered carbocyclic rings, to yield the alkaline salt of the corresponding beta,beta-dicyano-alpha-hydroxyvinyl compound and then acidifying said alkaline medium to precipitate the corresponding free acid.

5. Process of preparing a beta,beta-dicyano-alpha-hydroxyvinyl organic acid, which comprises hydrolyzing in an aqueous alkaline medium at a temperature below 100° C. a C-tricyanovinyl compound in which the C-tricyanovinyl group is attached to a carbon of a ring selected from the group consisting of 5-membered N-heterocyclic and 6-membered carbocyclic aromatic rings, to yield the alkaline salt of the corresponding beta,beta-dicyano-alpha-hydroxyvinyl compound and then acidifying said aqueous medium to precipitate the corresponding free acid.

6. A process as defined in claim 5 wherein the hydrolyzing is carried out by heating within the range of 50° to 100° C. and heating is stopped as soon as the C-tricyanovinyl compound is hydrolyzed.
